J. HOWARD WEATHERLOW AND FREDERICK W. SEYMOUR, OF FLUSHING, NEW YORK.

GRADUATED PLUG AND SOCKET.

Application filed March 25, 1921. Serial No. 455,703.

To all whom it may concern:

Be it known that we, J. HOWARD WEATHERLOW and FREDERICK W. SEYMOUR, both citizens of the United States, residing at Flushing, in the county of Queens and State of New York, have invented certain new and useful Improvements in Graduated Plugs and Sockets, of which the following is a specification.

10 This invention relates to electrical appliances and has particular reference to fuses or sockets relating thereto.

In our extensive experience in the inspection and installation of electrical appliances we have observed that a very common source of danger lies in the fact that fuse plugs of high capacity are employed in connection with circuits of relatively low capacity, thereby defeating to a large extent the 20 very purpose for which fuse plugs are intended. In other words, in a circuit calculated for carrying a relatively small load and guarded by a fuse plug as it should be that will make it impossible for the circuit to be overloaded and so rendered dangerous, if a fuse plug be employed in said circuit that has sufficient carrying capacity to sustain an overload on the circuit without blowing or fusing, the circuit is thereby immediately rendered dangerous. Accordingly, we have noted that fuse plugs are employed 30 more or less indiscriminately as to their carrying capacity with reference to the circuits, and so whether intentionally or not 35 plugs are inserted in place of other plugs previously blown out, that are dangerously too heavy for the places or currents into which they are inserted.

Among the objects, therefore, of this invention is to establish and maintain a predetermined correlation between a circuit and the fuse plug whereby it will be impossible or practically impossible for the circuit to be overloaded because of the use of a plug 45 of too high a capacity.

More specifically, by this invention it is provided that a plug having a fuse wire calculated for a heavy current cannot be inserted into a socket pertaining to a circuit 50 of low capacity, although it may be possible for a low capacity plug to be inserted and used in the socket pertaining to a high capacity circuit.

More specifically we provide a socket or receptacle comprising one contact which 55 may be similar to that usually employed while the other contact is adjustable to vary the depth to which the fuse plug may be introduced thereinto.

Another object of the invention is to provide a fuse plug of predetermined effective length whereby on the introduction thereof into the receptacle connection will not be made between the receptacle contacts if the 60 plug is of a capacity too high for that particular receptacle.

A still further object of the invention is to provide a fuse plug having a novel and peculiar type or design of renewable fuse wire, so that the same plug may be used 70 repeatedly by a very simple fitting thereinto of successive fuses.

As another object, as a corollary to the preceding object, provision is made that only fuses of a predetermined capacity may 75 be used in connection with certain plugs.

A still further object of the invention is to provide a renewable fuse including a terminal to which the wire is attached, with means to prevent accidental dropping out 80 of place of the terminal when the plug is being removed from its receptacle, thereby preventing any possibility of a short circuit at such time.

With the foregoing and other objects in 85 view the invention consists in the arrangement and combination of parts hereinafter described and claimed, and while the invention is not restricted to the exact details of construction disclosed or suggested herein, 90 still for the purpose of illustrating a practical embodiment thereof reference is had to the accompanying drawings, in which like reference characters designate the same parts in the several views, and in which— 95

Figure 1 is a longitudinal sectional view of one form of our improvement and which may be understood as pertaining to a relatively low capacity circuit.

Fig. 2 is a face view of the receptacle, the 100 plug being omitted.

Fig. 3 is a side elevation, partly in section, of a fuse plug adapted for a higher capacity than that of Fig. 1.

Fig. 4 is a face view of the plug shown 105 in Fig. 3.

Fig. 5 is a detail view indicating a plug is so made that its hole 12 is of selective or graduated fuse wires will receive properly a predetermined size or design of terminal 19. To readily adapt these porcelain bodies 11 to the different sizes or shapes of terminals it may be desirable to employ a hollow rivet 20, or its equivalent in the hole 12, the rivet having a hole therethrough corresponding to the terminal intended for use in that particular plug, and the rivet itself may be readily adaptable to the hole 12 even though the casting of the body 11 may not be perfectly accurate in all cases.

Fig. 6 is a detail view indicating one of many means for preventing accidental dropping out of the fuse terminal from the plug.

Referring now more specifically to the drawings we indicate a plug 10 comprising a body 11 usually made of porcelain or some other suitable insulating material, the otherwise closed end of the body being provided with a hole 12 through which the fuse terminal projects. This body is surrounded with a metal shell 13 provided ordinarily with an exterior right handed thread for co-operation with the metal shell 14 of the receptacle. The outer end of the shell 13 consists of a limit flange 15 lying in a plane perpendicular to the axis of the body 11 and against which a ring shaped shoulder 16 of insulation is threaded by co-operation with the aforesaid exterior thread of the shell 13 and adapted to be locked in such position by suitable means such as screws 17 passing through the flange 15 and into the ring or shoulder 16.

The body 11 of the plug may be made of any suitable length or size according to the use for which it is intended, and yet for our purpose the length of all plugs irrespective of the capacity may be substantially uniform while the effective length thereof may be variable according to the thickness of the rings or shoulders 16 as will be appreciated by comparing Figs. 1 and 3. That is to say, in a relatively low capacity equipment the ring 16 will be relatively thin so that the effective length of the plug will be greater than in the case of a high capacity plug whose ring 16' is thicker, making it impossible under ordinary circumstances for the effective length of the high capacity plug to engage the center contact of the lower capacity receptacle.

Again, a further distinction is made between the higher and the lower capacity plugs in that the fuse wires 18 or 18' thereof are of different sizes or different carrying capacities and, furthermore, the fusible wire portion is attached, as by soldering or otherwise, to a terminal 19 or 19' that is also distinctive in structure and appearance from the corresponding part of the fuse of any other capacity of fuse plug. As indicated in Fig. 5, for example, the fuse for a heavier capacity plug is provided with a square terminal 19 while the terminal 19' of the lower capacity device is of some other form such as triangular, so that any one familiar with these devices may know at a glance the carrying capacity of the fuse by observing the heads of terminals. The shank portions also of the terminals are of different sizes or shapes, and the body por-

70 The inner end of the fuse wire 18 may be fastened in any suitable manner to the shell 13 of the plug, as in connection with one of the screws 17. A cap 21 of any suitable nature may be connected to the outer end of the plug, as by being threaded upon the periphery of the ring 16. Thus the fuse wire 85 is protected as well as protecting the surrounding property from fire.

When the fuse blows out by the melting of the fuse wire 18 there is ordinarily nothing to prevent the dropping out of the terminal 19 from the hole 12 or hollow rivet. Any suitable mechanical means or device may be provided to prevent this circumstance, and as one means for accomplishing this result we indicate a keeper 22 in the form of a bent wire embracing the inner end of the terminal 19, so that when the plug is removed from its receptacle said terminal cannot drop into the receptacle and cause a short circuit between the two contacts of 100 the receptacle.

90 The socket or receptacle shown herein comprises any suitable terminals 23 and 24 for the circuit wires, the same being connected respectively with the shell 14 of the 105 socket and the center contact, comprising in this instance a member adjustable longitudinally along the axis of the socket or receptacle. This member is shown as a screw 25 having threaded engagement in a thimble 110 26 fixed in any suitable manner in the base 27 of the receptacle. The thimble is provided with a flange 28 shown as holding a washer 29 of insulation in the bottom of the receptacle. The inner end of the contact member 25 is adapted to be engaged by the head of the terminal 19 when the plug is in place, but to accommodate the position of this center contact to the effective length of the fuse plug, the center contact member 25 is adjustable along the axis aforesaid, an expedient easy to be performed by any authorized person when assembling the parts. It is not intended, however, that said contact member shall be readily adjustable by any one unauthorized so to do. In view of the fact that the fuse plug is ordinarily provided with a right handed thread on the exterior of the shell 13, it is preferable for the adjustable contact member 25 to be pro- 125 130

vided with a left handed thread, and so the insertion of the plug will not disturb the position of the screw.

We claim:

- 5 1. The combination with a receptacle, of a plug co-operating therewith, the plug including an externally threaded shoulder member of a graduated thickness serving to limit the extent of movement of the plug
- 10 into the receptacle, means to lock the shoulder member with its outer end substantially flush with the outer end of the plug, and a cap threaded upon said shoulder member.
- 15 2. In a device of the character set forth, the combination with a receptacle having two normally spaced contacts, and an externally threaded connecting member for said contacts insertable into the receptacle and having a limit flange at its outer end, of
- 20 means having threaded connection with the threaded member aforesaid and abutting against said limit flange to govern in accordance with the thickness of said means the distance which the connecting member is
- 25 movable into the receptacle to effect connection between the contact members.
- 30 3. In a device of the character set forth, the combination with a receptacle having two normally spaced contacts, of a connecting device insertable into the receptacle for connecting said contacts electrically, one of said contacts being adjustable to vary in a predetermined manner the depth to which the connecting member may be inserted into
- 35 the receptacle according to the capacity of the device.

4. The herein described receptacle comprising a base of insulation, a pair of electrical terminals carried by the base, and

means to connect said terminals electrically, 40 said connecting means including a thimble secured in the base and a screw adjustable along the thimble.

5. An electric plug provided flush with its outer end with an external stop shoulder of 45 graduated thickness to limit in a predetermined manner the depth to which the plug may be inserted into a receptacle.

6. In a plug, a threaded shell having a limit flange, a stop shoulder ring internally 50 threaded to screw onto said shell against said flange, said ring being externally threaded, and a closure for said plug having a threaded portion screwed onto the external threads of said ring.

7. A fuse plug comprising a shell having a flange, a stop shoulder secured against said shell flange at one end and extending therefrom toward the opposite end a measured distance proportioned to limit the insertion 60 of the plug into a socket in proportion to its capacity, said shell acting as one contact, a second contact, and a fuse member connecting said second flange adjacent to the outer end of the stop shoulder.

8. In a plug of the character described, a shell having threads extending from one end to the other and having an outwardly turned flange at its outer end, and a stop shoulder ring formed with internal threads fitting the threads on said shell and so turned thereon as to abut against said flange, and means extending through the said flange into the shoulder to lock the shoulder in place.

In testimony whereof we affix our signatures.

J. HOWARD WEATHERLOW.
FREDERICK W. SEYMOUR.
